(57) **CLAIM**

We claim the ornamental design for an animal-shaped food product, as shown and described.

DESCRIPTION

FIG. 1 is a front elevation view showing a first embodiment of our new design, comprising a animal-shaped food product, the back elevation view being the mirror image thereof;

FIG. 2 is a left side elevation view of the animal-shaped food product of FIG. 1;

FIG. 3 is a right side elevation view of the animal-shaped food product of FIG. 1;

FIG. 4 is a top plan view of the animal-shaped food product of FIG. 1;

FIG. 5 is a bottom plan view of the animal-shaped food product of FIG. 1;

FIG. 6 is a front elevation view showing a second embodiment of our new design, comprising a animal-shaped food product, the back elevation view being the mirror image thereof;

FIG. 7 is a left side elevation view of the animal-shaped food product of FIG. 6;

FIG. 8 is a right side elevation view of the animal-shaped food product of FIG. 6;

FIG. 9 is a top plan view of the animal-shaped food product of FIG. 6; and,

FIG. 10 is a bottom plan view of the animal-shaped food product of FIG. 6.
